CLAIM

The ornamental design for a dispenser pump bottle cap as shown and described.

DESCRIPTION

FIG. 1 is a perspective view of a dispenser pump bottle cap, showing our new design in a position of use with an exemplary dispenser bottle;

FIG. 2 is an elevation view thereof;

FIG. 3 is a further perspective view thereof, shown with the exemplary dispenser bottle removed to show aspect of the design not visible when combined;

FIG. 4 is a further elevation view thereof;

FIG. 5 is a bottom view thereof; and,

FIG. 6 is a perspective view thereof in an actuated configuration.

The broken lines are shown for the purpose of illustrating parts of the article as well as environmental subject matter of an exemplary dispenser bottle. None of the broken lines form part of the claimed design.
